TYPEWRITER ATTACHMENT

William C. Pfeiffer, Dayton, Ohio, assignor to The Egry Register Company, Dayton, Ohio, a corporation of Ohio

Application January 3, 1935, Serial No. 251

17 Claims. (Cl. 197—126)

This invention relates to improvements in attachments adapted to be used in connection with typewriters for supporting and feeding to the typewriter a plurality of strips of paper with interleaved carbon sheets therebetween.

It is an object of this invention to provide, in connection with a typewriter attachment, means for supporting the leading ends of strips of paper as they are written on, said means being also adapted to be used for supporting auxiliary and additional sheets of paper to be written upon and carbon sheets associated therewith.

It is also an object of this invention to provide a typewriter attachment which cooperates with the typewriter in feeding strips of paper to the typewriter according to the following method: (1) The strips are arranged in a writing position with the carbon sheets interleaved therebetween and the pins are mounted in the holes; (2) the strips and sheets are advanced during the process of writing and billing with the front pins in the holes; (3) after the billing and writing have been finished the pressure rolls are released from the platen and the sheets removed from the front pins; (4) immediately after such release the strips and interleaved carbon sheets are carried back by hand and spring action until the carbon sheets reach a point where they are released from the pressure rolls and the platen; (5) during this period you hold the rear pins out of the paper sheets; (6) the pressure rolls are again caused to cooperate with the platen to grip the strips of paper with the ends of the carbon sheets behind the platen; (7) the strips of paper with the carbon sheets interleaved therebetween are advanced until the first line of perforations shows in front of the typewriter platen; (8) the written-on bills and the strips of paper are then torn off.

These and other advantages will appear from the following description taken in connection with the drawings.

Referring to the drawings:

Figure 1 is a side elevation of the attachment shown in connection with a typewriter, and the strips of paper and interleaved carbon sheets in the position they have at the beginning of the writing period.

Figure 2 is a front elevation of the attachment applied to a typewriter, with the strips of paper and interleaved carbon sheets in the position they

have when the used parts of the strips of paper are to be torn off.

Figure 3 is a front elevation of the attachment and the typewriter with the strips of paper and carbon sheets interleaved and in the position they have at the beginning of the writing period.

Figure 4 is a rear elevation of the attachment.

Figure 5 is a somewhat diagrammatic view showing the position of the strips of paper and the interleaved carbon sheets at the end of the writing period.

Figure 6 is a section on the line 6—6 of Figure 4.

Figure 7 is a section on line 7—7 of Figure 4.

Figure 8 is a top plan view of the attachment with parts broken away.

Figure 9 is a section through one side of the attachment frame showing a pointer attached thereto.

Figure 10 is a perspective view of a plug to which one end of a tape member is attached.

Figure 11 is a front elevation of the attachment and part of the typewriter showing the attachment as used for supporting auxiliary sheets of paper and carbon sheets.

Figure 12 is a diagrammatic view showing in side elevation the mechanism of Figure 11.

The present attachment is adapted to be used in connection with a typewriter 1 which has the usual platen 2 and lever 3 for releasing the platen-engaging rolls. For the purpose of supporting the attachment, the typewriter has therein a bracket 4 provided with upstanding arms 5. Each arm has therein a clip 6 to receive a leg 7 attached to the lower end of the attachment frame by means of rivets and spacers 8. These legs are attached to sides 9 of the frame. These sides are connected at their lower ends by a lower bar 10 and at their upper ends by an upper bar 11 which is in front of the upper ends of the sides. The sides are also braced by diagonally extending braces 12. On the lower bar 10 are two brackets 13 which rotatably support the ends of the shaft 14. This shaft is provided adjacent each end with a sprocket 15. At the other end of the frame remote from the bar 10 there is a shaft 16 journaled at each end in one of the sides. On this shaft are sprockets 17 connected with the sprockets 15 by means of chains 18. Between the sprockets 17 there is rotatably mounted on the shaft 16 a roller or drum 18a used for supporting the strips of paper and holding them out of contact with the sprocket as they pass over the roller. One side is provided with a spring housing 19 which fits over one end of the shaft 16. To

15

20

25

30

35

40

45

50

55

this housing is attached one end of a coil spring 20 which has its other end attached to the shaft 16. This spring is brought under tension during the forward feeding of the strips of paper 5 and then the strips of paper are released, tend to reverse their travel.

Immediately above the shaft 16 and supported by the ends of the sides is a shaft 21 rotatably mounted in the ends and has thereon a pair of spaced guide discs 22 for engaging the edges of the superimposed strips of paper to properly guide them as they pass over the upper end of the frame and down to the typewriter. The sides of the frame are U-shaped with the arms thereof projecting toward the interior of the frame. On the rear of the frame is a rear plate 23, which is attached to the chains in any suitable manner, so that whenever the chains travel the rear plate moves with them. This plate engages at each end with the faces of the rear arms of the sides, and is provided with fingers 24 for engaging the front of the rear arms for holding the plate against the sides.

The upper end of the rear plate, at each end thereof, has a struck-up portion 25 which forms a bracket for supporting in a fixed position one end of a rod 26 which extends from one side of the frame to the other and serves to hold in proper position the strips of paper as they pass up the back of the frame. This rod has at each end adjacent the part 25, a guide disc 27 adapted to engage adjacent edges of the strips of paper. These discs are adjustable by means of screws 28.

On the lower edge of each end of the back plate is a bracket 29. At the inner end of each bracket is an arm 30. These arms rotatably support a roller or rod 31. On the outer end of each bracket 29 is an arm 32 to which is pivoted one end of a lever 33 by means of a pivot pin or bolt 34. These levers 33 are connected intermediate their ends by means of a back bar 35, to which one end of a coil spring 36 is attached, while the other end of the coil spring is attached to the rod 26. This spring tends to hold the back bar in engagement with the strips of paper.

Extending forwardly from the back bar are two pins 37 adapted to pass through holes provided therefor in the strips of paper for aligning the strips of paper and advancing the strips of paper when the chains and sprockets are caused to operate.

Slidably mounted on the front of the frame and in engagement with the front arms of the sides is a carbon carrier plate 38, which is also attached to the chain in any suitable manner so that whenever the chain moves this carbon carrier plate is caused to travel one way or the other. This carbon carrier plate engages the front surface of the sides and has at each end a tongue 39 to engage the rear of the front arms for the purpose of holding the carrier in cooperation with the side members forming the frame. At each end of the carbon carrier, and projecting downwardly therefrom, is a bracket 40 which has extending forwardly therefrom a pin 41 which has notches 42 intermediate its ends and at its forward end has an upwardly extending pin 43. These notches are adapted to receive the slotted ends of a spring plate 44 used for the purpose of holding the carbon sheets upon the pins. The upwardly projecting pins 43 serve to prevent the carbon sheets from becoming dislodged from the pins 41 in the event that the plate 44 is not used.

Each side member is provided adjacent its upper end with a stop 45 to limit the upward move-

ment of the carbon carrier during the backward movement of the strips of paper and the carbon sheets.

The upper bar 11 is held in spaced relation to the upper ends of the sides by means of spacer blocks 46. These blocks cause the upper bar to extend forward from the upper end of the sides and frame. To the central part of the upper bar there is attached a channel member 47 by means of an arm 48. On top of the upper bar, 10 are two spaced standards 49 connected together by means of a common foot member 50 attached to the upper bar by means of screws 51. These screws also pass through the arms 48 and serve 15 to hold the channel member in a rigid position with relation to the upper bar.

Extending through the standards intermediate their ends is a shaft 52 which supports between the standards a drum 53 rigidly attached thereto. 20 On one of the standards, fitting over one end of the shaft 52, is a spring housing 54 to which one end of a coil spring 55 is attached, while the other end of this coil spring is attached to one end of the shaft 52.

The channel member 47 has slidably mounted therein a channel-shaped slide member 56 which has in its lower end a plug 57, provided with a notch 58. In this plug extending across the notch 58 is a pin 59 to which one end of a tape 30 60 is attached, while the other end of this tape is attached to the drum 53. The lower end of the slide member is provided with a cross bar 61 attached at its medial point by means of screws 62 to the lower end of the slide member. These 35 screws not only serve to hold the cross bar on the slide member but also serve to hold the plug 57 within the lower end of the slide channel member. At each end of the cross-bar 61 and projecting forwardly therefrom is a pin 63. These pins are 40 adapted to pass through holes provided therefor in the leading edges of the sections of the strips of paper.

The slide member 56 is provided on its rear face with a stop 64 adapted to engage the lower 45 end of the channel member 47 for limiting the upward movement of the slide member. This stop may be adjusted with relation to the slide member. One of the side members 9 is provided with a pointer 65, as shown in Figs. 2, 3 and 9. 50

The strips of paper to be fed through the typewriter through the instrumentality of the attachment are indicated by the numeral 66, while the pile from which the superimposed strips of paper are fed is indicated by the numeral 67. These 55 strips are divided by cross-perforations into superimposed aligned tickets or bill forms. These tickets or bill forms have adjacent their leading ends holes 69 adapted to receive first the pins 37 located on the back bar 35, and thereafter the 60 pins 63 located on the cross-bar at the lower end of the slide member 56.

The slide member 56, the cross-bar 61 and the pins 63 thereon are adapted to be used for supporting in connection with the strips of paper and carbon sheets, additional and extra sheets of paper and carbon sheets in the manner shown in Figs. 11 and 12. In these Figures 11 and 12 the extra sheets of paper are indicated by the 70 numeral 70, while the extra carbon sheets are indicated by the numeral 71. These extra carbon sheets are not supported by the carbon carriers and are in no wise connected thereto physically. The extra sheets of paper are not operatively con- 75

nected to any part of the typewriter attachment except the pins 63.

Figure 1 shows the position of the various parts at the beginning of any writing operation. Figure 5 illustrates the position of the carbon sheets and strips of paper with relation to the apparatus at the end of any writing period.

From the time the strips and interleaved carbon sheets are in the position shown in Figure 1 until they are in the next successive similar position, the following operations take place:

(1) The arrangement shown in Figure 1 is the first step in the operation, which is the positioning operation.

(2) The second step is the advancement of the strips of paper and carbon sheets for billing and writing purposes. During this operation the strips of paper and sheets of carbon advance to the position shown in Figure 5.

(3) The next operation consists in releasing the pressure rolls from the platen of the typewriter, whereby the strips of paper and carbon sheets are released and may freely move independently of the platen.

(4) The strips of paper and interleaved carbon sheets are moved backwardly by hand in cooperation with the various springs until the advanced ends of the carbon sheets pass beyond the platen, so that the advanced ends of the strips of paper may be gripped between the pressure rolls and the platen without gripping the carbon sheets.

(5) The pressure rolls are again brought into engagement with the platen, thereby re-gripping the strips of paper so that a further rotation of the platen will advance the strips of paper without advancing the carbon sheets since the carbon sheets are free from the platen.

(6) The back bar has been moved backwardly, bringing the pins out of the holes in the strips of paper, thereby permitting the advancing of the strips of paper without the movement of the chains and sprockets.

(7) After the pins are released from the strips of paper, the strips of paper are caused to be advanced by the rotation of the platen until the second creases from the leading ends of the strips come to a position opposite the pointer 65. At this point in the operation the holes in the strips of paper are in position to receive the pins on the back bar.

(8) The back bar is next released so that the pins thereon are caused to enter the holes in the strips of paper.

(9) After the pins have entered the strips of paper the platen is further operated to advance the strips of paper and the carbon sheets therebetween.

(10) The bills written upon are then torn off; and

(11) The strips and carbon sheets interleaved therebetween are advanced for writing purposes to the position shown in Figure 1.

This series of steps forms a complete billing and advancing operation, and such steps are repeated with each successive billing operation.

By my invention I am enabled to secure the advantage of aligning and supporting the free ends of the sheets while they are being written upon, and of preventing them from falling over in front of the operator on the machine. They are yieldingly guided upwardly in aligned condition. I am enabled to have the further advantage of being able to add supplementary sheets between the ends of the main sheets that are being written upon, and their associated carbon sheets,

when such extra supplementary sheets are necessary.

It will be understood that I desire to comprehend within my invention such modifications as come within the scope of my claims and my invention.

Having thus fully described my invention, what I claim as new and desire to secure by Letters Patent, is:

1. In combination with a typewriter, an attachment therefor adapted to support and guide a plurality of strips of paper having spaced aligning holes therein to the typewriter comprising a frame having an upper bar, a spring operated drum on said upper bar, a guide member on said bar, a slide member including a transverse bar slidable in said guide member, means to connect the slide member to the drum and means comprising spaced pins on said slide member to engage the leading ends of the strips of paper by 20 engagement with the spaced aligning holes whereby the strips may be kept in alignment during the feeding thereof.

2. A typewriter attachment comprising a frame, a drum supported on the upper end of the frame, a guide member on the frame adjacent the drum, a slide member including a cross bar guided by the guide member, a tape connected at one end to the drum and at its other end to the slide member, and means on the bar comprising 30 spaced pins to support the leading ends of sheets of paper passing through the typewriter by registration with spaced holes preformed in the sheets of paper.

3. A typewriter attachment comprising a frame, a drum supported on the upper end of the frame, a guide member on the frame adjacent the drum, a slide member guided by the guide member, a tape connected at one end to the drum and at its other end to the slide member, 40 and means on the slide member to support the leading ends of the sheets of paper passing through the typewriter, said means comprising a cross bar on the lower end of the slide member, said cross bar having spaced pins thereon adapted 45 to register with holes preformed in the sheets.

4. A typewriter attachment comprising a frame adapted to engage at one end the typewriter and having on its other end a bar, a pair of spaced standards on the bar, a drum supported between the standards on a shaft journaled in the standards, a housing on one standard over one end of the shaft, a coil spring attached at one end to the shaft and at its other end to the housing, a guide member on said bar, a slide 55 member in the guide member, a tape connected at one end to the drum and at its other end to the slide member, and means including pins on the slide member to engage the leading ends of strips of paper passing through the typewriter 60 and supported by the frame by registration of the pins with holes preformed in the strips of paper.

5. A typewriter attachment comprising a frame adapted to engage at one end the typewriter and having on its other end a bar, a pair of spaced standards on the bar, a drum supported between the standards on a shaft journaled in the standards, a housing on one standard over one end of the shaft, a coil spring attached at one 70 end to the shaft and at its other end to the housing, a guide member on said bar, a slide member in the guide member, a tape connected at one end to the drum and at its other end to the slide member, and means on the slide member to en- 75

- gage the leading ends of strips of paper passing through the typewriter and supported by the frame, said means comprising a cross bar on one end of the slide member having spaced pins adapted to engage holes preformed in the ends of the strips of paper.
6. A typewriter attachment comprising a frame adapted to engage at one end the typewriter and having on its other end a bar, a pair of spaced standards on the bar, a drum supported between the standards on a shaft journaled in the standards, a housing on one standard over one end of the shaft, a coil spring attached at one end to the shaft and at its other end to the housing, a guide member on said bar, a slide member in the guide member, a tape connected at one end to the drum and at its other end to the slide member, and means on the slide member to engage the leading end of strips of paper passing through the typewriter and supported by the frame, said means comprising a cross bar on one end of the slide member and a pin on each end of the cross bar, said pins being constructed and arranged to engage spaced holes preformed in the ends of the strips of paper.
7. In a typewriter attachment, a frame adapted to be supported at one end on the typewriter, a drum on the other end of the frame connected by chains with a shaft at the first mentioned end of the frame to support a plurality of superimposed strips of paper, means on the chains moved by the strips of paper to support sheets of carbon interleaved between the strips of paper, and further means on the frame engaging the leading ends of the strips of paper to support sheets of paper and additional sheets of carbon interleaved with the strip and the first-named carbon sheets, said means comprising a vertically movable spring supported slide member having on one end a cross bar, said cross bar having means to engage holes preformed in the paper thereon.
8. In a typewriter attachment, a frame adapted to be supported at one end on the typewriter, a drum on the other end of the frame to support a plurality of superimposed strips of paper, means on the frame moved by the strips of paper to support sheets of carbon interleaved between the strips of paper, and means on the frame engaging the leading ends of the strips of paper to support sheets of paper and additional sheets of carbon interleaved with the strip and the first-named carbon sheets, said means comprising a vertically movable spring supported slide member having on one end a cross bar with pins thereon for engaging holes preformed in the paper and the additional sheets of carbon.
9. A typewriter attachment, comprising a frame, having at each end a pair of sprockets, chains engaging said sprockets, a back plate attached to said chains, a bar having pins thereon pivotally supported by said plate, a carbon-supporting plate attached to the chains, a spring operated drum on the frame at one end, a guide member on the frame adjacent the drum, a slide member slidably mounted in the guide member, a flexible member connecting the drum to the slide member, and means on the slide member to engage the leading end of strips of paper aligned by said pins and guided through the typewriter.
10. In a typewriter attachment, means for feeding endless paper sheets divided by transverse perforations at intervals, means for supporting carbon sheets to move with the paper sheets interleaved between them, said carbon sheets being of a length no greater than the dis-

tance between the transverse perforations in the paper sheets, said paper sheets having aligning apertures between each set of perforations, and means including transversely spaced pins adapted to extend through the apertures adjacent the free ends of the paper sheets beyond the leading edges of the carbon sheets for supporting the free ends of said paper sheets as they are written upon and for supporting extra paper sheets of sizes similar to the sizes of the sections of the paper sheets between perforations.

11. In a typewriter attachment, means for feeding endless paper sheets divided by transverse perforations at intervals, means for supporting carbon sheets to move with the paper sheets interleaved between them, said carbon sheets being of a length no greater than the distance between the transverse perforations in the paper sheets, said paper sheets having aligning apertures between each set of perforations, and means including transversely spaced pins adapted to extend through the apertures adjacent the free ends of the paper sheets beyond the leading edges of the carbon sheets for supporting the free ends of said paper sheets as they are written upon and for supporting extra paper sheets of sizes similar to the sizes of the sections of the paper sheets between perforations, said supporting means being arranged to align the main paper sheets and the extra sheets while moving said sheets and the carbon sheets bodily upwardly as they are being written upon.

12. In a typewriter attachment, means for feeding endless paper sheets divided by transverse perforations at intervals, means including transversely spaced pins adapted to cooperate with apertures in the rear edges of the carbon sheets at the corners thereof beyond the side edges of the paper sheets for supporting carbon sheets to move with the paper sheets interleaved between them, said carbon sheets being of a length no greater than the distance between the transverse perforations in the paper sheets, said paper sheets having aligning apertures between each set of perforations, means including laterally spaced pins engageable with apertures in the leading edges of the paper sheets beyond the leading edges of the carbon sheets for supporting the free ends of said paper sheets as they are written upon and for supporting extra paper sheets of sizes similar to the sizes of the sections of the paper sheets between perforations by engagement of the pins with apertures in the leading edges of said extra paper sheets, said supporting means being arranged to align the main paper sheets and the extra sheets while moving said sheets and the carbon sheets supported therebetween bodily upwardly as they are being written upon, and means for aligning the main paper sheets before they approach the place where they are written upon.

13. In a typewriter attachment, means for feeding endless paper sheets divided by transverse perforations at intervals, means including transversely spaced pins adapted to cooperate with apertures in the rear edges of the carbon sheets outside the side edges of the paper sheets for supporting carbon sheets to move with the paper sheets interleaved between them, said carbon sheets being of a length no greater than the distance between the transverse perforations in the paper sheets, said paper sheets having aligning apertures between each set of perforations, means including laterally spaced pins engageable with apertures in the leading edges of the paper

- sheets beyond the leading edges of the carbon sheets for supporting the free ends of said paper sheets as they are written upon and for supporting extra paper sheets of sizes similar to the sizes 5 of the sections of the paper sheets between perforations, said supporting means being arranged to align the main paper sheets and the extra sheets while moving said sheets and the carbon sheets supported therebetween bodily upwardly 10 as they are being written upon, means for aligning the main paper sheets before they approach the place where they are written upon, and means upon the removal of the last-mentioned paper aligning means for moving the main paper sheets 15 and carbon sheets backwardly bodily.
14. In a typewriter attachment, means for feeding endless paper sheets divided by transverse perforations at intervals, means including transversely spaced pins adapted to cooperate 20 with apertures in the rear edges of the carbon sheets outside the side edges of the paper sheets for supporting carbon sheets to move with the paper sheets interleaved between them, said carbon sheets being of a length no greater than the 25 distance between the transverse perforations in the paper sheets, said paper sheets having aligning apertures between each set of perforations, means including laterally spaced pins engageable with apertures in the leading edges of the 30 paper sheets beyond the leading edges of the carbon sheets for supporting the free ends of said paper sheets as they are written upon and for supporting extra paper sheets of sizes similar to the sizes of the sections of the paper sheets 35 between perforations, said supporting means being arranged to align the main paper sheets and the extra sheets while moving said sheets and the carbon sheets bodily upwardly as they are being written upon, means for aligning the main paper sheets before they approach the place where they are written upon, and means for moving the carbon sheets independently of the main paper sheets.
15. In a typewriter attachment, a frame adapted to be supported at one end on the typewriter, a drum on the other end of the frame connected 40 by chains for rotation with a shaft at the first-mentioned end of the frame to support a plurality of superimposed strips of paper having spaced preformed holes therein, means mounted on the chains and extending transversely thereof moved 5 by feeding of the strips of paper to support sheets of carbon interleaved between the strips of paper, and means on the frame including spaced pins constructed and arranged to engage holes preformed in the leading ends of the sheets of paper 10 beyond the leading edges of the sheets of carbon to support the sheets of paper and additional sheets of paper and of carbon interleaved therewith.
16. In a typewriter attachment, a frame adapted to be supported at one end of the typewriter, a drum on the other end of the frame to support a plurality of superimposed strips of paper and connected by means of a chain with a shaft at the first-mentioned end of the frame, means 20 on the chain comprising notched pins moved by the strips of paper by reason of the feed of the paper causing travel of the chain, said pins being adapted to support sheets of carbon interleaved between the strips of paper, and means on the frame engaging in apertures in the leading ends of the strips of paper to support the leading ends of the strips of paper and also additional sheets of paper and of carbon interleaved 25 therewith, said means comprising a vertically movable spring-supported slide member having on one end a cross bar with pins thereon for engaging holes preformed in the leading edges of the strips of paper and the additional sheets of carbon and paper.
17. A new article of manufacture for use as a typewriter attachment comprising a substantially vertical support, a resiliently urged reciprocating member therein including a cross bar carrying spaced pins for engaging holes preformed in the free ends of paper sheets passing through the typewriter, and yielding means adapted to cause the said cross bar to move the free ends of the sheets upwardly as the sheets 40 are written upon in the typewriter.
